US0D1020772S

(12) **United States Design Patent** (10) Patent No.: **US D1,020,772 S**
(45) Date of Patent: ** Apr. 2, 2024

(54) **DISPLAY SCREEN OR PORTION THEREOF WITH ICON**

(71) Applicant: **Adobe Inc.**, San Jose, CA (US)

(72) Inventors: **Yi-Ru Anny Chen**, San Francisco, CA (US); **Sonja Hernandez**, Berkeley, CA (US); **Ryan Hicks**, Danville, GA (US)

(73) Assignee: **Adobe Inc.**, San Jose, CA (US)

(**) Term: **15 Years**

(21) Appl. No.: **29/715,828**

(22) Filed: **Dec. 4, 2019**

Related U.S. Application Data

(62) Division of application No. 29/622,531, filed on Oct. 17, 2017, now Pat. No. Des. 872,765.

CLAIM

We claim the ornamental design for a display screen or portion thereof with icon, as shown and described.

DESCRIPTION

The sole FIGURE is a front view of a display screen or portion thereof with icon showing the claimed design.

The outermost broken-line rectangle illustrates the perimeter of a portion of a display screen and forms no part of the claimed design.

1 Claim, 1 Drawing Sheet
